DESIGN FOR A SCREW DRIVER

Clarence M. Skamser, Superior, Wis., and Vern S. Skamser, Los Angeles, Calif., assignors to Skamser Spindriver Corporation of America, Long Beach, Calif., a corporation of California

Application April 5, 1948, Serial No. 145,534

Term of patent 14 years

(Cl. D93—4)

To all whom it may concern:

Be it known that we, Clarence M. Skamser and Vern S. Skamser, citizens of the United States, residing at Superior, Wisconsin, and Los Angeles, California, respectively, have invented a new, original, and ornamental Design for a Screw Driver, of which the following is a specification, reference being had to the accompanying drawing, forming a part thereof.

Fig. 1 is a perspective view of a screw driver showing our new design, with portions of the shank broken away for illustrative purposes;

Fig. 2 is a top view of the screw driver of Fig. 1; and

Fig. 3 is a sectional view taken along the line III—III of Fig. 1.

We claim:

The ornamental design for a screw driver, as shown.

CLARENCE M. SKAMSER.
VERN S. SKAMSER.
